METHOD OF APPLYING A GETTER TO VACUUM DEVICES

Filed Sept. 12, 1922

FIG. 1.

FIG. 2.

FIG. 3.

INVENTOR
DANIEL S. GUSTIN

BY *J. Robert*
ATTORNEY

UNITED STATES PATENT OFFICE.

DANIEL SNYDER GUSTIN, OF NEWARK, NEW JERSEY, ASSIGNOR TO WESTINGHOUSE LAMP COMPANY, A CORPORATION OF PENNSYLVANIA.

METHOD OF APPLYING A GETTER TO VACUUM DEVICES.

Application filed September 12, 1922. Serial No. 587,654.

This invention relates to a method of applying a getter or clean-up agent to electrical devices and more particularly to the application of a getter or clean-up agent to a gas-filled, incandescent electric lamp.

An object of my invention is to simplify the method of applying a getter to a lamp.

Another object is to provide a method for applying a getter to a lamp part in such manner as to obtain the maximum efficiency of the getter.

A further object is to apply a getter in such manner as to be able to activate it to effect a quick clean-up action upon deleterious gases in all parts of a lamp.

A still further object is to provide a method whereby a getter may be applied to a gas-filled lamp without the use of a binder or other vehicle.

Other objects will be apparent from a reading of the following specification.

In certain types of electrical devices, particularly incandescent electric lamps of the gas-filled type, it is desirable to provide a material which, upon activation, will clean-up any residual gas that may have been left in the bulb after evacuation, or of occluded gases which may be given off, if the bulb of the lamp has been given what is termed a cold exhaust. A material of the above character is known in the art as a clean-up agent.

In lamps of the gas-filled type, it has been found undesirable to use a getter or clean-up agent which is carried in a binder or other vehicle. It has been found that, by the use of getters as heretofore used, the decomposition of the binder releases certain carbonaceous substances that have a detrimental effect upon the life of the lamp.

The present method, therefore, provides for the application of a getter in its pure state and it has been found that, by utilizing the adherent property of the getter material to the mount, the desired results are obtained without the use of any binder or other foreign substance for carrying the getter. It has been common to apply getters to such portion of the inner structure of a lamp or other device as will subject the getter to sufficient heat to vaporize it. Various methods of applying getters have been employed; for instance, the bead or similar mass of getter material has been deposited on the mount, or the mount may have been dipped in a solution in which the getter ma-

terial is carried in suspension and thus deposited.

In certain devices, a relatively large piece of getter material is applied to the internal structure of a vessel and vaporized. In gas-filled lamps, however, it is not possible to use a large piece of getter material, inasmuch as sufficient heat cannot be transferred thereto to cause its vaporization. On the other hand, if such a mass could be activated it is believed that too much discoloration within the lamp would result, since, when a mass of getter material is decomposed, it gives a sputtering action or melts gradually. This is particularly true where the heat is not intense enough to provide for the efficient vaporization of the material of the mass.

In the present invention, a getter material is applied in the powdered state, and any suitable portion of the interior of the lamp may be dipped, in, or otherwise coated with, the pure getter substance, particularly aluminum powder, which has been found to cling to certain portions of a lamp as, for instance, the filament or parts of the mount, and a getter so disposed may be subsequently activated when the lamp is lighted.

It has been found preferable to dip a mount into a receptacle containing powder of any substance that will give the getter action. Aluminum powder has, however, been found to give good results when employed in practicing my method. By dipping the mount into the powdered material, the powder becomes well distributed over a given area of the filament and, when activated, serves to clean-up the entire atmosphere within the bulb. This manner of distributing the getter material also provides for the rapid action of the getter since it is obvious that, with the thin layer applied by dipping, the filament may be heated to a considerably less degree than is necessary when a comparatively large amount of getter material is used in a concentrated mass.

Considerable advantage is, therefore, derived from the fact that the getter may be activated with a filament of relatively low temperature since there will be less alteration in the filamentary structure. The vaporization of getters which require the heating of a filament to a relatively high temperature tends to make the filament brittle, and a lamp gettered by my method will

have a filament more tenacious and, therefore, more readily adapted for general handling and transportation, which is a practical advantage in lamp manufacture.

5 The invention will be more clearly understood by reference to the accompanying drawing which shows an application of my invention to an electrical device, one of the standard gas-filled lamps being shown as 10 an example.

Fig. 1 is a view, in elevation, of a mount during the dipping operation;

15 Fig. 2 shows a mount in a holder and a bulb positioned in a given relation thereto, jaws for holding the bulb and a holder for the exhaust tube being indicated in dotted lines; and,

Fig. 3 shows a finished lamp of the gas-filled type.

20 In the embodiment of the invention shown, the mount may consist of the usual stem having an arbor 5, flare tube 6 and exhaust tube 7, as well as the leading-in wires 8, which are sealed into the press 25 9 of the stem in the usual manner.

The mount, as shown, is provided with a ring-type filament 11 carried on support wires 12. The mount may be dipped into a powdered getter 13 contained in a suitable receptacle 14, and dipped mounts may 30 be placed in a rack preparatory to their incorporation with a bulb and other lamp parts.

35 The gettering operation, as provided by my method, may be readily combined as a step in the manufacture of lamps. It will be understood that lamp mounts are sealed into bulbs by certain lamp-making machines which are well known in the art. When 40 operating such machines, the operator usually picks up a mount, places it in a holder 16 of a machine in a given position and positions the bulb between jaws 17, as indicated in dotted lines, over the mount. The 45 machines then operate to heat certain portions of the mount and the bulb, whereupon other mechanical elements are actuated to effect a union of the mount to the bulb.

50 During this operation, which is known as the sealing-in operation, an operator may, without any appreciable loss of time, dip a mount into a powdered material prior to

the positioning of the mount in the sealing-in machine. For this purpose, a receptacle 55 of any suitable shape may be conveniently located. When aluminum powder is used, the dipping operation is very quickly accomplished since this powder adheres to the dipped portions of the mount. The operator may quickly dip the mount, shake off any excess material and then insert the mount into the sealing-in machine.

60 The amount of getter material applied to a mount may be governed by the size of 65 the particles of the powder or by the extent to which the mount is dipped into the powder. Various expedients have heretofore been tried for efficiently gettering lamps of the gas-filled type but, owing to the supposed need of a binder or other vehicle for carrying the getter material, efficient results 70 have not been obtained. By my method, however, I have avoided the necessity of using any other material for carrying the 75 getter and am able to use a gettering substance, such as aluminum, to produce the desired high vacuum. The production of a 80 high vacuum by the vaporization of the aluminum seems to indicate that a reaction occurs directly with any oxygen and, 85 because the aluminum is distilled off and has no protecting film of oxide, it is in a state to react directly with water to form the hydroxide which is, in itself, a good dehydrating agent.

90 Although I have described what, at the present time, may be considered a preferred embodiment of my invention, it is to be understood that the method is utilizable with other devices and with getters of different characters.

95 What is claimed is:

1. The method of applying powdered clean-up-agent material to a vacuum device 95 which comprises dipping a portion of the internal structure of said device into such material.

100 2. The method of applying a getter to an electric incandescent lamp which comprises dipping a portion of the lamp mount into powdered aluminum.

In testimony whereof, I have hereunto subscribed my name this 11th day of September, 1922.

DANIEL SNYDER GUSTIN.
